UNITED STATES PATENT OFFICE.

LOUIS A. SCHMIDT, OF NEW YORK, N. Y., ASSIGNOR TO R. HOE AND CO., OF NEW YORK,
N. Y., A CORPORATION OF NEW YORK.

MARGINAL PRINTING PLATE.

Original application filed December 1, 1921, Serial No. 519,042. Divided and this application filed November 28, 1922. Serial No. 603,755.

To all whom it may concern:

Be it known that I, LOUIS A. SCHMIDT, a citizen of the United States, residing at New York city, county of Kings, and State 5 of New York, have invented certain new and useful Improvements in Marginal Printing Plates, fully described and represented in the following specification and the accompanying drawings, forming a 10 part of the same.

In a copending application Serial No. 519,042, filed December 1, 1921, of which this application is a division, there is disclosed a device for marginal printing, that 15 is, a device by which the margin space usually formed between two printing plates is utilized for printing. In the application above identified, this marginal printing device is in the form of a narrow supplemental 20 plate arranged to be placed in the margin space at one side of a main printing plate or between two main printing plates, and this narrow supplemental plate may be locked up by a sidewise movement of the 25 plates widthwise of the cylinder as described therein.

Under some circumstances, however, it is desirable to effect a lock up of these supplemental plates by a movement independent 30 of or additional to the sidewise lock up, and it is the especial object of the present invention to provide a simple construction whereby a circumferential locking movement may be given the narrow supplemental plates 35 independent of the sidewise lock up.

With this and other objects not specifically referred to in view, the invention consists in certain novel parts and arrangements which will be fully described in connection with the accompanying drawings, 40 and the novel features pointed out in the claims hereunto annexed.

In these drawings—

Figure 1 is a sectional end view of the 45 improved construction for effecting the lock up of the plate, the plate being shown in unlocked position.

Figure 2 is a similar view showing the plate locked.

Figure 3 is a detail sectional view taken 50 on line 3—3 of Fig. 2.

Figure 4 is a detail sectional view taken on line 4—4 of Fig. 2.

Referring now to these drawings, there

is shown a plate support in the form of 55 a cylinder 1, this cylinder being of any usual or desired construction. Supported on this cylinder is a main printing surface which, in the particular construction illustrated, includes a pair of main printing plates 2, 3. Spacing these plates are stops in the form of sliding blocks 4. These blocks, in the particular construction illustrated have a sliding movement widthwise 60 of the cylinder, as by rods 5, manipulated in any suitable manner, as for instance, by the construction illustrated in my copending application above referred to.

These blocks act to provide a margin 70 space between the main plates, and in this margin space is positioned a supplemental plate, this supplemental plate being marked 6 and provided with a printing surface which extends substantially across the margin space when the plates are in locked position, this printing surface being unbroken.

In accordance with the invention, means 75 are provided whereby the supplemental plate 6 may be given a locking movement independent of any movement it may have 80 widthwise of the cylinder, and in the particular construction illustrated, this movement is one circumferentially of the plate support so that the plates may be locked in position relatively to the main plates 85 and then, if desired, given a movement sidewise of the cylinder relatively to or with the main plates to effect a final lock up.

While the specific construction for effecting this may be somewhat varied, in the 90 particular construction shown, the supplemental plate is cast with a flange or projection 7, this flange extending preferably circumferentially of the plate, clear spaces 8 being left on each side of this flange at 95 intervals along the plate. At suitable intervals between the spaces this flange is widened, as indicated at 9, and these widened portions are formed with bevelled sides, indicated at 10 forming locking shoulders. 100 These bevelled sides are arranged to take into a groove 11, having correspondingly bevelled sides 12 formed in the blocks 4, it being understood that these blocks are provided in sufficient numbers about the cylinder. With this construction the plate may be locked in position in the blocks by 105 a movement circumferentially of the cylinder.

der by placing it in the position shown in Fig. 1 in which position the narrow part of the projection 7 will lie in the groove of the block, and then rotating the plate 5 to the position shown in Fig. 2, this rotation of the plate bringing the thickened portion 9 of the projection 7 in under the sides of the groove in the block. With this construction, therefore, the plate may be 10 readily placed in and removed from its printing position on the cylinder. After the plate has been positioned, the blocks, as before stated, may be moved, if desired, widthwise of the cylinder to lock up the 15 two main plates.

With the construction illustrated and described, a very simple construction has been provided for mounting the supplemental plates on and removing them from the 20 cylinder, and while the invention has been shown in its preferred form, it will be understood that certain changes and variations may be made in the particular structure and arrangement illustrated, and that 25 the invention is not to be limited to this.

What I claim is.

1. In a marginal printing mechanism, the combination with a plate support, of a main printing plate mounted thereon so as to leave 30 a margin space at one end of the plate, a supplemental printing plate secured on the support and having an unbroken printing surface for printing in the margin space at the end of the main plate, and means for locking up the supplemental plate by giving the plate a movement circumferentially of the plate support.

2. In a marginal printing mechanism, the combination with a plate support, of a pair 40 of printing plates on the support arranged end to end with a margin space between, a narrower supplemental printing plate in the

margin space between the plates, means for effecting a sidewise movement of the supplemental plate and main plates, and means for 45 effecting a locking of the supplemental plate independently of such sidewise movement.

3. In a marginal printing mechanism, the combination with a plate support, of a pair of printing plates on the support arranged 50 end to end with a margin space between, a narrower supplemental printing plate in the margin space between the plates, means for effecting a side lock up of the supplemental and main plates, and means for locking up 55 the supplemental plate by a movement circumferentially of the plate support.

4. In a marginal printing mechanism, the combination with a curved plate support, of a pair of printing plates on the support, 60 blocks in the support spacing the plates to form a margin, a narrower supplemental printing plate for printing in the margin, a groove in the blocks having locking shoulders, and a projection on the plate having 65 widened portions engageable with the shoulders by a circumferential movement of the plate.

5. In a marginal printing mechanism, the combination with a curved plate support, of 70 a pair of printing plates on the support, blocks in the support spacing the plates to form a margin, a narrower supplemental plate for printing in the margin, projections on the block having outer bevelled sides and 75 inner sides formed to provide locking shoulders on each side of a groove extending between them, and a projection on the plate having widened portions engageable with the shoulders by a circumferential 80 movement of the plate.

In testimony whereof, I have hereunto set my hand.

I OUIS A. SCHMIDT.
